SHEET FEEDING

Leonard Baker, Hillsdale, N. J., and George A. Martin, Pearl River, N. Y., assignors to Dexter Folder Company, Pearl River, N. Y., a corporation of New York

Application August 8, 1942, Serial No. 454,138

21 Claims. (Cl. 271—31)

This invention relates to improvements in a method and apparatus for the continuous feeding of sheets of material one at a time from a supply in which the sheets thereof are disposed in an on-edge position, as distinguished from feeding such sheets from either the top or bottom of a pile of stacked sheets. Our improved sheet feeder is particularly adapted for feeding sheets of cardboard, fiber board, woodboard, box board and also for feeding metal sheets of various types, such for instance, as those fed to a cold roll mill after the same have been annealed and manually separated by the sheet "openers."

Heretofore on-edge feeders have been of two general classes: first, those in which the sheets are fed from a supply thereof supported in an on-edge position, but inclined away from the direction in which the sheets are fed, and second, those in which the sheets are fed from a supply thereof, also supported in an on-edge position, but inclined in, or toward, the direction in which they are fed.

In feeders of the first class, that is, those in which sheets are fed from a position inclined away from the direction of feeding, it has been necessary to provide a movable or adjustable supporting means for the sheets which must be interrupted in its operation, that is, the supporting means must be removed or otherwise manipulated in order to enable an operator to replenish the supply of sheets being fed thereby with the result that such on-edge feeders are not continuous in their operation. Such feeders may also be described as having an operating sequence somewhat similar to the method of feeding sheets one at a time from the top of a pile of stacked sheets because it is necessary to stop the feeder when a new pile of sheets must be supplied thereto.

In feeders of the second class, namely those in which sheets may be continuously fed from an on-edge position inclined toward the direction of feeding, the supply of sheets is preferably required to rest upon some fixed supporting means whereby the sheet to be fed must first be moved from its position against said support where it reposes under the weight of other sheets in the supply. This operation of removing a sheet disposed in such an on-edge position is somewhat analogous to that of feeding, one at a time, the lowermost sheet from a pile of stacked sheets, because it presents the problem offered in such cases of handling the weight of a pile of sheets resting upon the sheet to be fed. Moreover, in feeders of this class there is presented the addi-

tional problem of having to lift the sheet to be fed and at the same time bend it in order to be able to deliver it bottom edge foremost to the forwarders.

An important object of our invention therefore is to provide a continuous on-edge feeder to which sheets may be supplied as occasion requires and in which the sheets being fed therefrom are disposed in a position inclined away from the direction in which they are fed.

Another object of our invention is to provide an on-edge feeder mechanism which may be continuously loaded with or receive supplies of sheets initially inclined in the direction in which they are fed, and in which the operation of said mechanism is such that before said sheets are delivered to the forwarders the inclination thereof is reversed and the lower edges of said sheets are fanned out or separated from one another to facilitate the delivery thereof.

A further object of our invention is to provide an improved method of continuously feeding sheets from a supply thereof in which the sheets are initially disposed in said supply in an on-edge position inclined in one direction and while conveying the sheets so disposed toward the point of delivery or removal simultaneously separating the lower edges of said sheets one from another and reversing the angularity of said sheets so that they may be delivered one at a time from the supply.

Further objects and advantages of our invention include the novel sequence of operation taught thereby and features of construction and arrangement of elements which in combination comprise a device of the class described and which objects and advantages will be apparent from the following description thereof written in connection with the accompanying drawings 40 showing a preferred embodiment thereof, and in which

Figure 1 shows a side elevation of a preferred form of our sheet feeding apparatus and one adapted to practice our novel method of continuously feeding sheets from an on-edge position.

Figure 2 shows a sectional view of the feeder in Figure 1 and showing further structural details thereof.

Figure 3 is a plan view of the feeder shown in Figures 1 and 2.

Figure 4 is an enlarged view of the ratchet mechanism.

Referring now to the drawings, it will be seen that our feeder means comprises a base or frame

structure having side plates 10 supported and held spaced from one another by means of cross bars 11. The side plates 10 are shaped to form suitable legs or supports 12, preferably fastened, by means of angle sections 13, to the floor or other suitable foundation proximate the mechanism with which the feeder is to be used.

Mounted above this base structure is what we shall call, for the want of a better name, a vertically adjustable traveling sheet supporting mechanism indicated generally, on Figure 2, by the numeral 14. This sheet supporting mechanism 14, comprising a pair of side plates 15 supported and held in spaced relationship to one another by cross bars of staybolts 16, is mounted above the base 10-11 by means of four rack bars 17, the upper ends of which are connected in any suitable way to the side plates 15 through the medium of bosses 18 formed thereon. As shown in Figure 1, each of these bosses 18 is bored out to receive the upper end of one of the rack bars 17 and is provided with set screws 19 formed to secure the same therein. It will be noted that the staybolts 16 are located only along the upper edges and forward ends of the plates 15 so that the space between said plates is otherwise unobstructed, for reasons which presently will become apparent.

The lower end of each of the rack bars 17 is slidably and vertically mounted for movement in a pair of axially aligned bearings 20-21 formed on the side plates 10, as shown in Figures 2 and 3. A pair of rods 22, each provided with a pair of spaced pinions 23 keyed thereto, are suitably journaled in the side plates 10 so that each of the pinions 23 is mounted to mesh with, operate and support a corresponding rack bar 17 and through said bars support the sheet mechanism 14 for vertical adjustment. A sprocket 24 keyed to each of the rods 22 carries a sprocket chain 25 which serves as the means for rotating the rods 22 and pinions 23 in unison when either of the rods are rotated. Crank means 26, see Figure 3, keyed to an end of one of the rods 22 is provided for rotating the same and comprises any suitable mechanism, not shown, for holding said crank means, including the rack and pinion means, in any position of vertical adjustment to which it is set.

It will now be understood that our mechanism 14 is adjustably supported above the base or frame structure by the rack and pinion means above described and that, by rotating the crank means 26, the said mechanism 14 may be manually raised and lowered as desired with respect to said frame structure and thereby adjust the same to receive and support sheets of different dimensions.

Referring still further to the supporting mechanism 14, it will be seen that proximate the forward end 30 of each of the plates 15, and disposed, respectively, proximate the inside surfaces of said plates, are a pair of spaced sprockets 31 which are carried by and keyed to a shaft 32 having the ends thereof suitably journaled in said side plates 15. At the other end and on the inside of each of said side plates 15 are rotatably mounted, respectively, such as on studs 33, a pair of sprockets 34. It will be seen from the drawings that a sprocket 31 and a pair of sprockets 34 are disposed, as a group, in a plane spaced from the inside surface of each side plate 15 and support and drive respectively a pair of spaced endless conveyor chains 35 each having a plurality of inwardly projecting notched lugs 36 secured thereto at equidistant intervals throughout the 70 75

length thereof, so that the said chains and lugs are adapted to travel in the direction of the arrows on Figure 2. Any suitable means, such as slots 37 provided for adjusting the location of the studs 33 and sprockets 34, are employed so that the chains 35 may be adjusted and held taut as shown in Figures 1 and 2.

On the inside surface of each side plate 15 is also mounted track means for sheet supports comprising a pair of horizontal parallel bars 38 disposed one above the other and having the forward ends thereof rounded as at 39. The space between the rearwardly extending ends of bars 38 is closed by a vertical bar 40. A sheet support guide 41 is mounted in spaced relation with respect to said bar 40. Track means 38, 40, 41, such as just described, is disposed on the inside surface of each side plate 15 and located in a plane spaced from said plates a distance somewhat greater than that between the chains 35 and said side plates, as shown in Figure 3. The mounting and spacing of track means of the form here shown is effected by suitable bolts 42, see Figure 2, and spacers 43, see Figure 3. Each of the sprockets 31 is provided with deep notches 44 circumferentially spaced one from another a distance equal to the space between the lugs 36. A plurality of sheet supports 45 preferably in the form of straight bars each having their ends disposed respectively in notches 46 of corresponding lugs 36 on the spaced chains 35 are adapted to be propelled in one direction across the upper and in another direction beneath the lower bars 38 when the chains 35 are driven in the direction of the arrows, as shown in Figure 2.

It will be understood that since the spaced chains 35 are simultaneously and continuously driven in the direction shown by the arrows by the sprockets 31 mounted on the common shaft 32 that the bars or sheet supports 45 resting on the track means 38 with their ends disposed in notches 46 of corresponding lugs 36, will be propelled laterally toward the sheet support guides 41. When each support 45 successively reaches the guides 41 the ends of said support will be brought to and disposed opposite the upper ends of the spaces 47 formed between the bars 40 and the guides 41 whereupon the support 45 is free to drop to the bottom thereof from the notches of the upper lugs 36 which at that time are projecting downwardly. Moreover, the corresponding lugs 36 on the spaced chains 35 are positioned so that when a pair of upper lugs have brought to and deposited in the space 47 a sheet support 45 a pair of lower lugs 36 with their notches 46 projecting upwardly will at that time be disposed in alignment with the bottom of the spaces 47 to receive the support 45 when it drops and thereafter laterally propel the same along the lower and to the upper side of the track means 38, as shown, with the aid of the sprockets 31 and the notches 44 which serve to enable the sprockets to lift the supports 45 from the lower to the upper track when they reach the forward end of the mechanism 14.

Constructed on the base structure between the side plates 10 and below the traveling sheet supporting mechanism 14, we provide a conveyor means indicated generally by the figure 50 in Figure 3, and upon which the lower edges of sheets to be fed are adapted to rest in an inclined position as shown in Figure 1. It will be understood that our conveyor means 50, in combination with said traveling supporting mechanism 14 are adapted to convey sheets continu-

ously in the direction of the arrows, shown in Figures 2 and 3, toward sheet forwarders to be hereinafter described. While our conveyor means may be constructed in different ways such as employing a traveling chain type of conveyor, when, for instance, it is desired to feed metal sheets; and while said conveyor means may be such as will move at a uniform speed ratio throughout the length thereof; the form of feeder here shown as a preferred embodiment of our invention comprises a belt or tape conveyor means comprising a plurality of conveyor sections adapted to move, respectively, at different speeds for conveying the sheets from the point where they are received into the feeder to the point of delivery therefrom.

What may be described as the first or slow speed conveyor section of our conveyor means 50 comprises a plurality of endless belts 51 disposed about and extending laterally from a roller 52 having a shaft 53 journaled in the side plates 10 to a plurality of spaced driving pulleys 54 keyed as at 55 to a shaft 56 which is also journaled in the plates 10. It will be understood that the roller 52 and the pulleys of this and the other conveyor sections to be hereinafter described are preferably of the same size and diameter and positioned so that the upper surfaces of said belts are disposed in a common substantially horizontal plane as shown in Figures 1 and 2.

The second or intermediate speed conveyor comprises a plurality of endless belts 57 disposed about loose pulleys 58 mounted on the shaft 56, but between the pulleys 54, and a corresponding number of pulleys 59 keyed as at 60, to a shaft 61 journaled in the side plates 10. Similarly, a third and high speed conveyor comprising a plurality of endless belts 62 disposed about loose pulleys 63 mounted on the shaft 61, but between the pulleys 59 thereof, and a corresponding number of pulleys 64 keyed, as before described, to a shaft 65 also journaled in the side plates 10.

The shaft 65 projects through one of the side plates 10 and has its end supported at 66 by means of a bracket 67 secured in any suitable way to the side plates 10, which bracket also affords support to a stub shaft 68, as at 69, which is disposed at right angles thereto and extending toward the rear of the feeder. Bevel gears 70, keyed respectively to the shaft 65 and stub shaft 68 in meshing relation, are provided to enable the former to drive the latter as and for the reasons to be described hereinafter.

On the end of the shaft 65 between the side plate 10 and the support 66, are mounted and keyed thereto a sprocket wheel 71 and a toothed ratchet 72. Also mounted on the shaft 65 for an oscillatory movement is a pawl plate 73 carrying a pawl 74 adapted when actuated to cooperate with the teeth on the ratchet 72 and intermittently rotate or advance the shaft 65 in a clockwise direction and at the same time drive the belts of the third or high speed conveyor section 62 in the direction indicated by the arrows. The ratchet and pawl mechanism 72-74 is adapted to be actuated by means of a link 75 connecting the pawl plate 73 to a disc 76 keyed to the end of a drive shaft 77 which is driven continuously in a clockwise direction by any suitable mechanism such as the chain and sprocket means 78-79 shown in the drawings. It will be understood that the shaft 77 is a part of the conveyor mechanism 80 of the machine to which it is desired to feed continuously, one

at a time, sheets from our improved on-edge feeder mechanism.

The second or intermediate conveyor 57 is driven by the shaft 65 operating through the sprocket 71 and a chain 81 cooperating with a sprocket 82 somewhat larger in diameter than the sprocket 71, which sprocket is keyed to the shaft 61. Similarly the first or low speed conveyor 51 is driven by means of a sprocket 83 having the same diameter as that of the sprocket 82 and also keyed to the shaft 61, a chain 84 and a sprocket 85 having a diameter somewhat larger than that of the sprockets 82 and 83 and keyed to the shaft 56. It will now be understood that the relative speed ratios of our several conveyor sections will be in proportion to the diameters of the sprockets 71, 82 and 85 which are employed in driving them from the shaft 65. We have found that it is desirable to run the first or low speed conveyor 51 at approximately the same rate of speed as the chains 35.

The sheet supporting mechanism 14 is driven by the shaft 65 through the bevel gears 70 and means comprising a shaft 90, bevel gears 91, connecting the shaft 90 with a splined telescopic shaft 92, which in turn drives the shaft 32 of the mechanism 14 by means of bevel gears 93. It will be understood that the telescopic shaft 92 makes it possible for this driving mechanism 30 to operate the mechanism 14 at any elevation at which it is set and that the diameters of the several bevel gears driving the same are such that the speed ratio between said mechanism and that of the conveyor is properly established. The shafts 90 and 92 are rotatably mounted on the side plates 10 and 15 in any suitable way such as by means of bearings 94.

In combination with the conveyor means 50 we provide a governor or sheet detector 95 located near the forward or delivery end of the conveyor 62, which detector comprises a plurality of levers 96 mounted to rock on a shaft 97 carried by the side plates 10, and a pawl mask 98 disposed adjacent the ratchet 72 and keyed to the end of a shaft 99 disposed parallel to the shaft 97, and also carried by the plates 10. The levers 96 are movably connected to the shaft 99 by means of links 100, see Figure 2, pivotally connected to arms 101 keyed to the shaft 99. A pin 102, see Figure 3, projecting from the side of the pawl 74 is adapted to slide over the top of the mask 98 as it is oscillated back and forth by the pawl plate 73.

Between the conveyors 50 and 80 is suitably mounted any well known form of sheet feeding mechanism comprising a feed roller 105 and drop rollers 106, adapted to cooperate therewith, so that the points of contact or bite between said rollers are located in substantially the same plane as that of the belts of the conveyors 50 and 80. Suction feeding devices 107 are provided and mounted in any suitable way for delivering sheets to the feed rollers 105-106, as for instance on a shaft 108 extending from one side frame 10 to the other. It will be understood that the means for operating the feed rollers 105, 106 and also the means for operating the suction feeding devices 107 are all well known and, per se, form no part of our present invention. Suffice it to say, however, that when sheets have been conveyed and presented to the suction feeding devices 107 and disposed in proper position to be lifted and forwarded thereby into the feeding mechanism 105-106, that the weight of the sheets resting upon the governor 95 is sufficient to lift the mask

98 through the medium of the links 100 and arms 101 so that the pawl 14 cannot cooperate with the ratchet wheel 72 and the driving mechanism for the conveyor mechanism is disabled until the suction feeding devices 107 have removed the sheets from the governor, at which time it will, due to the weight of the mask 98, be raised by gravity, or any other suitable means not shown, and the pawl mask 98 lowered whereby the ratchet and pawl mechanism will again operate to convey sheets to the feeding mechanism. This governor or detector means, therefore is controlled by the operation of said sheet forwarding means to periodically disable the means for operating both the conveyors and sheet supporting means whenever the forwarding means has before it sheets upon which it may operate.

With particular reference to Figure 1 of the drawings, it will be understood that in the operation of our feeder, stacks or groups of sheets are first disposed in an on-edge position resting upon the conveyor section 51, and leaning against one of the traveling bars or sheet supports 45 which, as pointed out above, will at that time preferably be running at substantially the same speed ratio as said conveyor section. The lower edges of the sheets so placed in the feeder will successively pass from the conveyor 51 to conveyor 57, and finally to conveyor 62. As the conveyors 51, 57 and 62 move toward the suction feeding devices 107 and feeding rollers 105, 106, at the forward end of our feeder, the lower supports 45 of the sheet supporting mechanism 14 also move in the same direction but at a rate somewhat slower than that of the conveyors 57 and 62, so that when the sheets reach the forward end of our feeder the angularity thereof will be reversed and the lower edges of the sheets will be fanned out somewhat. It will be understood that the several supports 45 are dropped into position to support successive groups or stacks of sheets inclined in either of two directions and that when the feeder has been operated sufficiently to be fully supplied as shown in Figure 1, the said groups may be identified one from another by the letters A, B, C and D.

In the form of the device shown here it will be understood that by virtue of the variable speeds at which our several conveyor sections 51, 57 and 62 travel forwardly the extent to which the lower edges of the sheets are fanned out will be progressively increased and become very pronounced as shown by the sheets in group D at the right hand side of the supply shown in Figure 1, and the degree of change in the angularity of the said sheets accentuated, so that when a plurality of groups of sheets, such as those indicated generally by the letters A, B, C and D of Figure 1, have been disposed in the machine and permitted to progress therethrough, sheets from the pile D may be delivered easily, one at a time, lower edge foremost, into the bite of the feed rollers 105—106 by the suction feeding devices 107. Here it will be understood that the sheet in group D to be fed, indicated by the letter E in Figure 1, is removed from what may be described as the top of an inclined pile of on-edge sheets and at a time when its weight has been transferred from, or removed from, the support 45 upon which it once rested. This is because the preceding sheet support 45 against which the pile D was initially resting when it was placed in the machine as pile A, has continued to move with the chains 35 on its course and the weight of the sheets of group D have been progressively shifted or removed

therefrom due to the change in angularity thereof, and the action of fanning out or separation of the lower edges of said sheets, until the sheets of said group D are supported at the time of delivery on the next succeeding or following support 45 instead of the support immediately preceding said group, in order to dispose them in a favorable position to be acted upon by the sheet forwarders.

10 It will also be understood from our drawings and description how the variation in adjustment, or the distance between the conveyor mechanism 50 and the supporting mechanism 14 makes it possible to vary the angularity of the sheets resting on the conveyor. The amount that the lower edges of the sheets are fanned out at the time of presentation to the forwarders is determined by the number or relative speeds of the conveyors. Moreover, when a single conveyor means is used, instead of one comprising a plurality of conveyor sections as above described, the rate of travel of said conveyor will always be greater than the rate at which the sheet supports 45 are moved toward said forwarders.

25 Stops 109, carried by a bar 110, mounted in the side plates 10, are provided to prevent the sheets of group D, see Figure 1, from being moved by the conveyor too close to the suction feeding devices 107.

30 Having now particularly described a preferred embodiment of our invention, including our novel method for continuously feeding sheets in an on-edge position, it will be understood that various modifications in the configuration, composition and disposition of the component elements which in combination constitute our improved apparatus, as well as modifications in the selective combination or application of the various steps of our improved method of feeding sheets, may occur to those skilled in the art, especially after being able to benefit from the teachings set forth herein. Accordingly, no unnecessary limitation is intended by the phraseology of the foregoing description of our invention made in accordance with the illustrative drawings which accompany the same.

45 What we claim is:

1. A sheet feeder comprising forwarding means operable upon a sheet presented thereto in an on-edge position inclined away therefrom; in combination with mechanism for initially receiving and supporting a sheet in an on-edge position inclined toward said sheet forwarders and for conveying the same toward, and presenting the same to, said forwarding means; said mechanism comprising means for reversing the inclination of said sheet after the same has been received in said mechanism and before being presented to said forwarding means.

50 2. A sheet feeder comprising sheet forwarders for removing, one at a time, sheets from a supply thereof presented thereto in an on-edge position inclined away therefrom; in combination with mechanism for initially receiving and supporting a supply of sheets in an on-edge position inclined toward said sheet forwarders and for conveying the same toward, and presenting the same to, said sheet forwarders; said mechanism comprising means for reversing the inclination of said sheet supply after the same has been received in said mechanism and before it is presented to said forwarders.

55 3. A sheet feeder comprising sheet forwarders for removing, one at a time, sheets from a supply thereof presented thereto in an on-edge po-

sition inclined away therefrom; and mechanism for initially receiving a supply of sheets disposed in an on-edge position inclined toward said sheet forwarders and for conveying the same toward, and presenting the same to, said sheet forwarders; said mechanism comprising means for reversing the inclination of said sheet supply after the same has been received in said mechanism and before it is presented to said forwarders in combination with detector means for controlling the operation of said mechanism in accordance with the operation of said sheet forwarders.

4. A device for feeding sheets from a supply thereof disposed in an on-edge position comprising forwarding means adapted to remove sheets one at a time lower edge foremost from a supply, conveyor means upon which a supply of sheets is adapted to stand and be conveyed toward said sheet forwarding means, and sheet supporting means disposed above said conveyor means also movable toward said sheet forwarding means, but at a rate of speed less than that of said conveyor means, and against which sheets resting on said conveyor means are adapted to be supported in positions inclined in either of two directions, with respect to said conveyor means, in combination with mechanisms operable at different speed ratios for simultaneously driving toward said forwarding means both said conveyor means and said sheet supporting means whereby the angle of inclination of said sheets is reversed.

5. A device for feeding sheets from a supply thereof disposed in an on-edge position comprising forwarding means adapted to remove sheets one at a time lower edge foremost from a supply, conveyor means upon which a supply of sheets is adapted to stand and be conveyed toward said sheet forwarding means, and sheet supporting means disposed above said conveyor means also movable toward said sheet forwarding means, but at a rate of speed less than that of said conveyor means, and against which sheets resting on said conveyor means are adapted to be supported in positions inclined in either of two directions, with respect to said conveyor means, in combination with mechanisms operable at different speed ratios for simultaneously driving toward said forwarding means both said conveyor means and said sheet supporting means whereby the angle of inclination of said sheets is reversed, and means controlled by the operation of said forwarding means for periodically disabling said driving mechanisms.

6. A device for feeding sheets from a supply thereof disposed in an on-edge position comprising forwarding means adapted to remove sheets one at a time lower edge foremost from a supply, conveyor means upon which a supply of sheets is adapted to stand and be conveyed toward said sheet forwarding means, sheet supporting means disposed above said conveyor means also movable toward said sheet forwarding means but at a rate of speed less than that of said conveyor means, and against which sheets resting on said conveyor means are adapted to be supported in positions inclined in either of two directions, with respect to said conveyor means, and means for varying the distance between said conveyor means and sheet supporting means, in combination with mechanisms operable at different speed ratios for simultaneously moving toward said forwarding means both said conveyor

means and sheet supporting means whereby the angle of inclination of said sheets is reversed.

7. A device for feeding sheets from a supply thereof disposed in an on-edge position comprising forwarding means adapted to remove sheets one at a time lower edge foremost from a supply, conveyor means upon which a supply of sheets is adapted to stand and be conveyed toward said sheet forwarding means, a plurality of spaced sheet supporting bars against which groups of sheets resting on said conveyor means are adapted to be supported in positions inclined in either of two directions with respect to said conveyor means, and means mounting said bars for movement toward said sheet forwarding means at a rate of speed less than that of said conveyor means, in combination with mechanism operable at different speed ratios for simultaneously moving toward said forwarding means both said conveyor means and said bars whereby the angle of inclination of said sheets is reversed.

8. A device for feeding sheets from a supply thereof disposed in an on-edge position comprising forwarding means adapted to remove sheets one at a time lower edge foremost from a supply; conveyor means upon which a supply of sheets is adapted to stand and be conveyed toward said sheet forwarding means, said conveyor means including a plurality of conveyor sections adapted to be driven at different speed ratios, and means for driving said sections at different speed ratios; sheet supporting means disposed above said conveyor means also movable toward said sheet forwarding means and against which sheets resting on said conveyor means are adapted to be supported in positions inclined in either of two directions with respect to said conveyor means, and means moving said sheet supporting means toward said forwarding means at a rate of speed not greater than that at which any of said conveyor sections are driven, in combination with mechanism for simultaneously operating both said conveyor means and said sheet supporting means whereby the angle of inclination of said sheets is reversed.

9. A device for feeding sheets from a supply thereof disposed in an on-edge position comprising forwarding means adapted to remove sheets one at a time lower edge foremost from a supply; conveyor means upon which a supply of sheets is adapted to stand and be conveyed toward said sheet forwarding means, said conveyor means including a plurality of conveyor sections adapted to be driven at different speed ratios, and means for driving said sections at different speed ratios; sheet supporting means disposed above said conveyor means also movable toward said sheet forwarding means and against which sheets resting on said conveyor means are adapted to be supported in positions inclined in either of two directions with respect to said conveyor means, and means moving said sheet supporting means toward said forwarding means at a rate of speed not greater than that at which any of said conveyor sections are driven, in combination with mechanism for simultaneously operating both said conveyor means and said sheet supporting means whereby the angle of inclination of said sheets is reversed, and means controlled by the operation of said forwarding means for periodically disabling said operating mechanism.

10. A device for feeding sheets from a supply thereof disposed in an on-edge position comprising a plurality of spaced sheet supporting bar

means, sheet forwarding means, conveyor means adapted to support groups of sheets in an on-edge position with each said group leaning toward said forwarding means and against a preceding bar means, and mechanism for successively disposing each said bar means above said conveyor means in sheet supporting position and thereafter conveying toward said sheet forwarding means each said bar means in spaced relationship to one another along a plane parallel to said conveyor means, in combination with means for driving said conveyor means toward said sheet forwarding means, and means for simultaneously operating the aforesaid mechanism at a rate of speed less than that at which said conveyor means is driven, whereby said groups of sheets are successively caused to shift their position from that of leaning against a preceding bar means to that of thereafter leaning against an immediately succeeding bar means.

11. A device for feeding sheets from a supply thereof disposed in an on-edge position comprising a plurality of spaced sheet supporting bar means, sheet forwarding means, conveyor means adapted to support groups of sheets in an on-edge position with each said group leaning toward said forwarding means and against a preceding bar means, mechanism for successively disposing each said bar means above said conveyor means in sheet supporting position and thereafter conveying toward said sheet forwarding means each said bar means in spaced relationship to one another along a plane parallel to said conveyor means, means for driving said conveyor means toward said sheet forwarding means, and means for simultaneously operating the aforesaid mechanism at a rate of speed less than that at which said conveyor means is driven whereby said groups of sheets are successively caused to shift their position from that of leaning against a preceding bar means to that of thereafter leaning against an immediately succeeding bar means, in combination with means controlled by the operation of said forwarding means for simultaneously disabling both the conveyor driving means and mechanism for operating said bar means.

12. A device for feeding sheets from a supply thereof disposed in an on-edge position comprising a plurality of spaced sheet supporting bar means, sheet forwarding means, conveyor means adapted to support groups of sheets in an on-edge position with each said group leaning toward said forwarding means and against a preceding bar means, and mechanism for periodically dropping said bar means one at a time into group separating position above said conveyor means and thereafter conveying toward said sheet forwarding means each said bar means in spaced relationship with one another along a plane parallel to said conveyor means, in combination with means for driving said conveyor means toward said sheet forwarding means, and means for simultaneously operating said dropping and conveying mechanism at a rate of speed less than that at which said conveyor means is driven, whereby said groups of sheets are successively caused to shift their position from that of leaning against a preceding bar means to that of thereafter leaning against an immediately succeeding bar means.

13. A device for feeding sheets from a supply thereof disposed in an on-edge position comprising a plurality of spaced sheet supporting bar means, sheet forwarding means; conveyor means adapted to support groups of sheets in an on-edge

position with each said group leaning toward said forwarding means and against a preceding bar means, said conveyor means comprising a plurality of conveyor sections adapted to be driven at different speed ratios, and means for driving said conveyor sections at different speed ratios; and mechanism for periodically dropping said bar means one at a time into group separating position above said conveyor means and thereafter conveying toward said sheet forwarding means each said bar means in spaced relationship to one another along a plane parallel to said conveyor means, in combination with means for driving said conveyor means toward said sheet forwarding means, and means for simultaneously operating said dropping and conveying mechanism at a rate of speed less than that at which said conveyor means is driven whereby said groups are successively caused to shift their position from that of leaning against a preceding bar means to that of thereafter leaning against an immediately succeeding bar means.

14. The method of continuously presenting sheets for removal one at a time from a supply thereof in which the said sheets are disposed in an on-edge position comprising the steps of initially placing the sheets of said supply in an on-edge position inclined in the direction in which they are to be removed with their upper edges foremost, and simultaneously conveying said supply of sheets bodily toward a point of removal and in the direction in which they are to be removed, and rotating the same to reverse the inclination thereof whereby the said sheets are finally inclined in a direction away from the direction in which they are to be removed and presented for removal, one at a time, with their lower edges foremost.

15. The method of continuously positioning sheets for removal one at a time from a supply thereof in which the said sheets are disposed in an on-edge position comprising the steps of initially placing the sheets of said supply in an on-edge position inclined in the direction in which they are to be removed with their upper edges foremost, and while rotating said sheets to reverse the inclination thereof, conveying the same bodily in the direction in which they are to be removed toward a point of removal, whereby the said sheets are finally inclined in a direction away from the direction in which they are to be removed and presented for removal with their lower edges foremost.

16. The method of continuously positioning sheets for removal one at a time from a supply thereof in which the said sheets are disposed in an on-edge position comprising the steps of initially placing the sheets of said supply in an on-edge position inclined in the direction in which they are to be removed and with their upper edges foremost, and while rotating said sheets about a horizontal axis located between their upper and lower edges to reverse the inclination thereof, conveying the same bodily in the direction in which they are to be removed toward a point of removal, whereby the said sheets are finally inclined in a direction away from the direction in which they are to be removed and presented for removal with their lower edges foremost.

17. The method of continuously feeding sheets for removal one at a time from a supply thereof in which the said sheets are disposed in an on-edge position comprising the steps of initially placing the sheets of said supply in an on-edge

position inclined in the direction in which they are to be fed with their upper edges foremost, and simultaneously conveying said supply of sheets bodily in the direction in which they are to be fed toward a point of removal, and rotating the same to reverse the inclination thereof whereby the said sheets are finally inclined in a direction away from the direction in which they are to be fed and presented for removal, one at a time from said supply, with their lower edges foremost. 10

18. The method of continuously feeding sheets for removal one at a time from a supply thereof in which the said sheets are disposed in an on-edge position comprising the steps of initially placing the sheets of said supply in an on-edge position inclined in the direction in which they are to be removed and with their upper edges foremost, and while rotating said sheets to reverse the inclination thereof, conveying the same bodily in the direction in which they are to be removed toward a point of removal, whereby the said sheets are finally inclined in a direction away from the direction in which they are to be removed and presented for removal with their lower edges foremost, thereafter seizing the sheets of said supply so presented, one at a time, and successively feeding the same therefrom lower edge foremost.

19. The method of continuously feeding sheets for removal one at a time from a supply thereof in which the said sheets are disposed in an on-edge position comprising the steps of initially placing the sheets of said supply in an on-edge position inclined in the direction in which they are to be removed and with their upper edges foremost, and while rotating said sheets about an axis located between their upper and lower edges to reverse the inclination thereof, conveying the same bodily in the direction in which they are to be removed toward a point of removal, whereby the said sheets are finally inclined in

a direction away from the direction in which they are to be removed and presented for removal with their lower edges foremost, and thereafter seizing the sheets of said supply so presented, one at a time, and successively feeding the same therefrom lower edge foremost.

20. The method of continuously presenting sheets for removal one at a time from a supply thereof in which the said sheets are disposed in an on-edge position comprising the steps of initially placing the sheets of said supply in an on-edge position inclined in the direction in which they are to be removed with their upper edges foremost, and simultaneously conveying 15 said supply of sheets bodily toward a point of removal and in the direction in which they are to be removed, rotating the same to reverse the inclination thereof, and progressively fanning out the lower edges of the sheets in said supply 20 whereby the said sheets are finally inclined in a direction away from the direction in which they are to be removed and presented for removal, one at a time, with their lower edges foremost.

21. The method of continuously positioning sheets for removal one at a time from a supply thereof in which the said sheets are disposed in an on-edge position comprising the steps of initially placing the sheets of said supply in an on-edge position inclined in the direction in which they are to be removed with their upper edges foremost, and while rotating said sheets to reverse the inclination thereof, conveying the same 25 in the direction in which they are to be removed toward a point of removal, and progressively 30 fanning out the lower edges of said sheet supply, whereby the said sheets are finally inclined in a direction away from the direction in which they are to be removed and presented for removal with their lower edges foremost and separated one 35 40 from another.
